United States Patent Office.

CYRUS F. GILLETTE, OF SPARTA, WISCONSIN.

Letters Patent No. 63,500, dated April 2, 1867.

IMPROVED BED BOTTOM.

The Schedule referred to in these Letters Patent and making part of the same.

TO ALL WHOM IT MAY CONCERN:

Be it known that I, C. F. GILLETTE, of Sparta, in the county of Monroe, and in the State of Wisconsin, have invented certain new and useful Improvements in "Bed Bottoms;" and do hereby declare that the following is a full, clear, and exact description thereof, reference being had to the accompanying drawings, and to the letters of reference marked thereon, making a part of this specification.

My invention relates to that class of bedsteads upon which cords are used to support the mattress.

In the annexed drawings, A represents the usual form of bedstead. Upon the two sides and end rails of the bedstead I place a series of pulleys in a horizontal position, or rollers, b, for the bed-cord to pass around. These pulleys readily turn in their places, and are set sufficiently apart to suit the cord or rope, a. B B represent slats which shield the pulleys and the cord in their proper places. At the foot of the bedstead, to one of the posts, is a shaft which passes through and beyond the said post, as shown in fig. 1. This shaft has a small ratchet, f, and dog, e, to hold it as desired. One end of the bed-cord I attach to the shaft, and pass it around the several pulleys in the usual way, securely fastening the other end to a pin, x, in one of the rails. D represents a key which fits over the end of the shaft C, for the purpose of winding the cord around the shaft, thereby tightening or loosening the said cord as required.

In a bed bottom having the cord passing around a series of pulleys, b b, I claim the arrangement of the slats B B, placed above the pulleys, when in combination with the shaft C, as specified.

In testimony that I claim the foregoing Letters Patent, I have hereunto set my hand and seal this 17th day of December, 1866.

CYRUS F. GILLETTE.
